COMBINED HAIR LIFTER AND HAIR COMB

Anthony Battaglia, 1703 NE. 21st Ave., Miami, Fla.

Filed Feb. 14, 1966, Ser. No. 920

Term of patent 14 years

(Cl. D86—8)

FIG. 2

FIG. 1

FIG. 3

FIG. 4

FIGURES 2 and 3 are front and rear edge views respectively, and

FIGURES 4 and 5 are rear and front end views respectively.

I claim:

The ornamental design for a combined hair lifter and hair comb, substantially as shown.
